W. L. BRADLEY,
TRAFFIC SIGNALING DEVICE,
APPLICATION FILED NOV. 8, 1915.

1,254,971.

Patented Jan. 29, 1918.

FIG. 1

UNITED STATES PATENT OFFICE.

WILLIAM L. BRADLEY, OF RICHMOND, VIRGINIA.

TRAFFIC-SIGNALING DEVICE.

1,254,971.

Specification of Letters Patent. Patented Jan. 29, 1918.

Application filed November 8, 1915. Serial No. 60,373.

To all whom it may concern:

Be it known that I, WILLIAM L. BRADLEY, a citizen of the United States, residing at Richmond, in the county of Henrico, State 5 of Virginia, have invented certain new and useful Improvements in Traffic-Signaling Devices; and I do hereby declare the following to be a full, clear, and exact description of the invention, such as will enable others skilled in the art to which it 10 appertains to make and use the same.

This invention relates to a traffic signaling device.

An object of the invention resides in the 15 provision of a simple device which may be readily operated so as to indicate the opening and closing of traffic on cross streets.

A further object of the invention resides in so constructing the device that a visible 20 as well as an audible signal will be given.

With these and other objects in view, such 25 as will appear as my description progresses, my invention comprises the combination and arrangement of parts as set forth in and falling within the scope of the appended claims.

In the drawing:

Figure 1 is an elevational view of my device;

Fig. 2 is an enlarged vertical sectional view showing the manner in which the umbrella stem and the signal carrying standard are mounted;

Fig. 3 is an enlarged detail of the bell and 35 bell ringing mechanism, looking at the side of the same;

Fig. 4 is a horizontal sectional view showing the bell ringing mechanism; and

Fig. 5 is a section on line 2—2 of Fig. 2.

Referring to the drawing by reference 40 characters wherein like parts are indicated by like characters throughout the several views:

In the drawing, I have illustrated a base 1 from which a post 2^a extends vertically upward, which post is of tubular formation. Secured to this post between its ends and extending outwardly at right angles thereto 45 is a clamping member 3 in which a sleeve 4 is mounted and secured, the said sleeve extending into the base. This sleeve termi-

nates short of the upper end of the post 2 and is provided with a circumferential slot 5 which extends partly around the sleeve. Secured to the upper end of the post 2^a is a bearing member 6 and rotatably mounted in this bearing member and in the sleeve 4 is a signal carrying standard 7, on which a collar 8 is formed, which collar bears against the upper end of the sleeve 4 and maintains the 60 standard in its proper position. This standard 7 is provided with an offset portion 9 for the accommodation of an umbrella in a manner which will later appear. The upper end of the standard 7 extends vertically and secured thereto are cross arms 10 and 11 which extend at right angles to each other. These cross arms have lamp carrying chambers 12 on the ends thereof, which chambers are provided with bull's eyes 13. The arms are 65 further provided with spaced plates 14 on which the word "Open" and the word "Closed" appear, the former being on the arm 11 to each side of the standard 7 and the latter on the arm 10 to each side of the said 70 standard. The inner end of the lamp chamber 12 on each arm is open so that the light may pass between the plates 14 and shine through the letters of the said words, the letters being made of transparent material. 75 The ends of the chambers 12 are closed by drop doors 15 so that the lamps may be readily placed in and removed from the chambers.

Secured to the lower end of the standard 7 80 and extending outwardly through the slot 5 in the sleeve 4 is an operating handle 16 by means of which the standard may be turned, the movement of the handle being limited by its contact with the ends of the slot 5. It 85 will be obvious that the standard 7 may be turned by means of the handle 16 so that the signaling arms on the upper end of the standard may be turned in the desired direction.

A collar 17 is mounted on the upper end of the post 2^a and is provided with a thumb screw 18 which passes through an opening in the post. Removably mounted in the upper end of this post is an umbrella 19, the 90 stem 20 of which extends into the post and may be held therein by the thumb screw 18.

It will be obvious that with this particular arrangement of the standard 7 and the umbrella, that the latter may be removed, readily, when desired.

5 In order that an audible signal may be given as the handle 16 and the signaling arms are turned, I have provided a flanged block 21 which extends between the sleeve 4 and the post 2^a and is held in place by 10 means of a plate 22 and a bolt 23. On one end of this bolt a gong 24 is mounted while a knocker 25 is pivotally mounted on the plate 22, at 26 and the head of which is normally pulled toward the bell by a coil 15 spring 27. This knocker is provided with a shoulder 28 and in order that the knocker may be lifted from the bell as the handle 16 is turned, I have provided a trip lever 29 on one end of which a dog 30 is pivotally 20 mounted, the said dog being provided with an abrupt face 31 and a cam face 32. The dog is further provided with a finger 33 which is adapted to contact with the under face of the lever and this finger is normally 25 held in contact with the said lever by a spring 34, which spring also tends to draw the end of the lever on which the dog is mounted downwardly. The other end of the lever is provided with a cam 35 which is 30 mounted in the path of movement of the handle 16 so that when the handle is moved in either direction, the end of the lever 29 will be depressed and the dog 30 raised so that the knocker 25 will be raised from the 35 bell.

When the handle 16 is thrown to the left from the position shown in Fig. 4 of the drawings, the cam 35 is depressed, as will be understood upon reference to Fig. 3 of the 40 drawings, moving the opposite end of the lever 29 with the dog 30 upwardly. During this movement, the abrupt or flat face 31 of the dog brushes against the shoulder 28 and lifts the knocker 25. During this movement 45 of the lever 29, pivoting of the dog with respect to the lever is prevented by reason of the contact of the finger 33 of the dog with the lower face of the lever. This upward movement of the dog continues until the dog 50 has passed from engagement with the shoulder 28, when the knocker 25 is released and is thrown violently against the gong by the action of the spring 27. At this time, the handle 16 is still in contact with the cam 55 35 but directly thereafter, the handle in its continued movement to the left, passes from the cam 35 and the spring 34 draws the lever 29 back to the position shown in Fig. 3. During this movement of the lever 29, the 60 cam face 32 of the dog strikes and rides over the shoulder 28, the dog moving on its pivotal connection with the lever 29 at this time. When the lever has returned completely to the position shown in Fig. 3 of

the drawings, the cam face of the dog has 65 passed from the shoulder 28 and the dog resumes its position with its finger 33 against the lever 29 and its abrupt face 31 beneath the shoulder 28. Then when the handle 16 is moved back again, it reengages the cam 70 35 and the operation is repeated.

It is sometimes desirable to lock the standard 7 and the sleeve 4 together so that the former cannot move and I have provided the sleeve with an aperture 36 which is adapted 75 to register with a similar aperture in the standard 7. A pin 37 is mounted on a chain 38 which chain is secured to the block 21 and this pin is adapted to be inserted in the aperture 36 and the aperture in the standard 80 7 which registers therewith and to prevent the turning of the standard. When the standard is locked in this position, the signal arms are turned in such positions that they will neither indicate that the streets are 85 opened or closed but rather will extend in angular relation to the streets so that traffic may pass each way at will.

The collar 8 is provided with the letters N and E which indicate to the operator the 90 position of the signal arms, that is whether or not the east or north traffic is open.

A clamp 39 is mounted above the signal arms 10 and 11 and has a reflector 40 for directing the rays downwardly. 95

While I have illustrated and described a particular embodiment of my invention, it has merely been for the sake of convenience and I do not wish to be limited to that particular embodiment as it is obvious that numerous changes may be made in the details of construction without departing from the spirit of the invention or exceeding the scope of the appended claims. 100

What I claim is:—

1. In a traffic signaling device, the combination with a sleeve, of a relatively movable standard mounted therein, signal arms secured to the upper end of the standard, a post mounted adjacent the sleeve and having 110 an umbrella mounted on the upper end thereof, the said standard having an offset portion for the accommodation of the umbrella and a handle for rotating the standard. 105

2. In a device of the class described, the combination with a stationary sleeve, of a signal arm carrying standard rotatably mounted in said sleeve, a bell located adjacent the sleeve, a knocker for said bell, a lever for actuating the knocker having a 115 cam on one end thereof and a handle secured to the standard, the cam being located in the path of movement of the handle so that it will be depressed upon the movement of the handle. 120

3. In a device of the class described, the combination with a stationary sleeve, of a signal arm carrying standard rotatably

mounted therein, a bell located adjacent the sleeve, a knocker for said bell, a lever for actuating the knocker having a two-faced cam and a handle secured to the standard

of the handle to a predetermined position with relation to each cam face. 10

In testimony whereof, I affix my signature, in the presence of two witnesses.

WILLIAM L. BRADLEY

5 and adapted when moved in opposite directions to engage these faces of said cams successively to actuate the lever, the said sleeve including means for limiting the movement

Witnesses:

GEORGE AINSLIE,
G. E. DAVISON.
